(57) CLAIM

The ornamental design for a textured handle packaging, as shown and described.

DESCRIPTION

This application is related to U.S. Patent Application No. 10/428,035 filed on May 2, 2003, the subject matter of which is incorporated herein by reference.

FIG. 1 is a perspective view of a first embodiment of a textured handle packaging showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view of a second embodiment of FIG. 1, the only difference being the textured portions under the handle, it being understood that all other surfaces are the same as those of the first embodiment.

The broken line showing of the environment is for illustrative purposes only and forms no part of the claimed design.
